UNITED STATES PATENT OFFICE.

JOHN FRED MOWAT AND GEORGE P. WARDLEY, OF JOLIET, ILLINOIS.

INSULATING WALLS.

Application filed December 24, 1925. Serial No. 77,472.

Our invention relates to method of and means for insulating the walls of coke ovens and particularly the ends of the regenerative chambers on the outside thereof to prevent the escape of heat from the regenerative chambers so that workmen in operating the coke ovens will not be subjected to the intense heat emanating from the walls and also for the purpose of confining the heat and preventing the loss thereof.

Another and further object of our invention is the provision of insulating means for use particularly upon the end walls of regenerative chambers of coke ovens in which the leakage around all pipes is eliminated and heat loss from this source is prevented.

Another and further object of our invention is the provision of heat insulating means which is applied to the walls of the oven so as to prevent the cracking of the outer wall due to the intense heat to which these walls are subjected.

Another and further object of our invention is the provision of heat insulating means for oven walls which is simple and efficient in operation and which effects a very material saving in the operation of a coke oven due to the retaining of the heat in the oven and preventing radiation thereof to the atmosphere so that the cost of operating the oven is materially decreased and also very materially lessens the cost of keeping the ovens properly heated to prevent cracking of the walls of the oven when the oven is idle. The insulation being on the outside of the oven walls also performs its function more satisfactorily than when placed between the walls of the oven which cannot be made too heavy because of the unequal expansion of a thick or heavy wall.

These and other objects of our invention will be more fully and better understood by reference to the accompanying sheet of drawings and in which:—

Figure 1 is a view partially in section of the end of the regenerative chamber of a coke oven having our invention applied thereto;

Figure 2 is a detailed sectional view of the regenerative walls shown in Figure 1, and

Figure 3 is a sectional view of a modified form of wall construction for a coke oven.

Referring now specifically to the drawings, a foundation 10, usually made of concrete or

the like, is shown having an air chamber 11 located therein from which a passage 12 leads to an air inlet pipe 13 through which the air passes into the checker work 14 underneath the section 15 within which the coke chambers of this type of oven are located. An outside wall 16 is provided which extends upwardly from the foundation 10 and having openings 17 therein for purposes of ventilation and the like, the wall 16 having a concrete platform 18 positioned therein which is supported by cross members 19 resting on the walls 16 at their outer ends and by the end walls of the regenerative chamber of the coke oven on their inner side. A gas main 20 is provided having a pipe 21 leading therefrom and through which gas is supplied to the combustion chambers adjacent the coking chambers of the oven 15, the gas being mixed with the heated air passing through the regenerative chambers 14 as is common in coke ovens of this type. Extending vertically along the ends of the coke oven is a plurality of buckstays 22, the said buckstays being spaced apart from each other and extending into the foundation 10 at their bottoms and being anchored in any suitable manner at their tops so as to form the supporting members for the end retaining walls of the coke oven. Adjacent the regenerative chamber 14 is a transversely extending wall 23 which is built up in the usual manner of fire brick and on the outside of which is a layer of insulating material 24 with a further wall 25 being built as an outer wall and which is composed of common brick or the like and forms the outer retaining wall of the regenerative chamber 14.

In our improved invention we add a wall or a heavy coating of insulating material 26 on the outside of the wall 25 and between the buckstays 22 on the outer side of which a retaining wall 27 of ordinary bricks is placed or this wall may be made up of sheet iron, steel or the like as may be desired, of sufficient strength to retain the insulating wall 26 in position so that the radiation of heat from the furnace wall is very materially reduced. The wall 26 may be composed of any well known heat insulating material such as silocel, filinsul, asbestos or the like, it being understood that the walls 26 and 27 are placed across the entire end of the regenerative chamber of the coke oven at each

end thereof so as to minimize and prevent the radiation of heat from the walls at these spaces to the largest extent possible.

In applying these walls to the furnace it may be done, either in the building of a new oven or in the addition of the two walls 26 and 27 to the ordinary standard construction of walls for the regenerative chambers. In the case of ovens which are already in service, the insulating material can be added to the wall and then the retaining wall 27 of common brick, sheet iron or other material superimposed thereon which is thereafter allowed to set, thus sealing all cracks in the wall due to the intense heat and also preventing very materially the radiation of heat from the walls.

In Figure 3 is illustrated a modified form of our invention and in which an inner wall 28 composed of fire brick is provided with a second wall 29 of ordinary brick, with a wall of insulating material 30 such as we have described above superimposed on the wall 29, and a retaining wall 31 of ordinary brick, sheet iron or the like being provided to hold the insulating material in proper position.

This construction is substantially the same as has been heretofore described except that the intermediate wall 24 is omitted.

While we have described more or less precisely the details of construction, we do not wish to be understood as limiting ourselves thereto, as we contemplate changes in form and the proportion of parts and the substitution of equivalents, as circumstances may suggest or render expedient without departing from the spirit or scope of our invention.

We claim:

A regenerator comprising in combination, retaining walls, checkerwork positioned within said retaining walls, an outer shell, and a filling of insulating material between said retaining wall and said outer shell, the insulating material and the retaining wall being independently movable with respect to each other and the outer shell in said retaining wall also being independently movable with respect to each other.

Signed at Joliet, Illinois, this 17th day of December, 1925.

GEORGE P. WARDLEY.
JOHN FRED MOWAT.
